POCKET-COMB CLIP

Application filed October 30, 1929. Serial No. 403,561.

My invention relates to and has for a purpose the provision of a clip particularly adapted, although not necessarily, for use in connection with pocket combs to detachably

5 secure the comb within a pocket so as to prevent the comb from falling from the pocket.

It is also a purpose of my invention to provide a clip for pocket combs which is structurally characterized by its simplicity of construction and consequent low cost of manufacture, and which is functionally characterized by its easy mode of application to a comb, and to combs of various sizes and having backs of various curvatures.

15 I will describe only one form of clip for pocket combs embodying my invention, and will then point out the novel features thereof in claims.

In the accompanying drawings:

20 Fig. 1 is a view showing a conventional form of pocket comb having applied thereto one form of clip.

Fig. 2 is a view showing the clip in end elevation and in applied position to a comb.

25 Fig. 3 is a view showing the clip in top plan and in applied position to a comb.

Fig. 4 is a view showing in plan a metal blank from which the clip is formed.

30 In carrying out my invention, the clip is formed from a blank of resilient material, preferably spring steel, the blank being shaped as illustrated in Fig. 4 to provide a body 15 of substantially rectangular outline and an extension 16 projecting from one end of the body and offset with respect to the major axis of the body. The body 15 is bent longitudinally and substantially in the form

35 of a U in order to provide a pair of companion jaws 17 connected by a rounded bight portion 18, as best illustrated in Fig. 2. These jaws 17 and bight portion 18 constitute a clamp which is adapted to embrace the back of a comb, and to facilitate the application of the clamp to the comb, the marginal edges of the jaws are flared outwardly as indicated

40 at 19. In order that the clamp may be applied to combs having straight or curved backs, the body 15 is formed with an opening 20 so as to divide the bight portion 18 into two parts sufficiently spaced that the curva-

ture of the comb back may not interfere with the proper application of the clamp to the comb.

The spacing of the jaw 17 is such that in applying the clamp to the comb it is necessary 55 to expand the jaws, and as a consequence to place the jaws under tension so that once the comb is inserted, the jaws will have clamping engagement with the comb, and thereby securely maintain the clip against accidental 60 displacement from the comb.

The extension 16 constitutes a tongue, and as illustrated in Figs. 1 and 3, it is bent rearwardly upon itself adjacent its point of connection with the body 15 in such manner as 65 to form an intervening curved portion 21 which functions as a spring to urge the tongue 16 in the direction of the body 15. From its point of connection with the portion 21, the tongue slants in the direction of the body 15, and its free end terminates in a head 22 which is slightly dished as shown. In order to lend strength to the tongue that it may not bend transversely and thus properly function to grip the pocket, it is curved 70 transversely as illustrated.

In practice, the clip is applied to the comb as illustrated in Figs. 1 and 2 so that the tongue 16 is disposed at one side of the comb. By extending the comb into the pocket so 75 that the head 22 is lowermost, the cloth forming the outer wall of the pocket may be extended between the tongue and the clamp so that under the resiliency of the tongue, the cloth is firmly gripped to retain the comb 85 against accidental displacement from the pocket.

Although I have herein shown and described only one form of clip for pocket combs embodying my invention, it is to be 90 understood that various changes and modifications may be made herein without departing from the spirit of the invention and the spirit and scope of the appended claims.

I claim:

1. A clip for pocket combs comprising a clamp including spaced jaws and a bight portion resiliently connecting the jaws, said bight portion having an opening therein to divide the latter into two spaced parts, and 95 100

a tongue resiliently connected to the clamp so as to be disposed at one side thereof.

2. A clip of the character described comprising a single piece of resilient material having a body of substantially rectangular outline bent longitudinally upon itself in the form of a U to form spaced resilient jaws and a connecting bight portion, said body being formed with an opening in the bight portion, a tongue disposed at one side of the major axis of the body and bent upon itself so as to be disposed at one side of the body and to be urged in the direction of the body, and a head on the free end of the tongue.

15 3. A clip for pocket combs as embodied in claim 2 wherein, the tongue is curved transversely and the head is dished.
